UNITED STATES PATENT OFFICE.

HARRY C. WAITE, OF CHICAGO, ILLINOIS, ASSIGNOR TO INTERNATIONAL HARVESTER CORPORATION, A CORPORATION OF NEW JERSEY.

INTERNAL-COMBUSTION ENGINE.

1,135,082.

Specification of Letters Patent. Patented Apr. 13, 1915.

Application filed June 3, 1914. Serial No. 343,853.

To all whom it may concern:

Be it known that I, HARRY C. WAITE, a citizen of the United States, residing at Chicago, in the county of Cook and State of Illinois, have invented certain new and useful Improvements in Internal-Combustion Engines, of which the following is a full, clear, and exact specification.

This invention relates to internal combustion engines, and more particularly to means for controlling the supply of fuel thereto and for igniting the same.

The main object of this invention is to obtain complete combustion of the heavier fuels, such as kerosene, in the combustion chamber of an internal combustion engine under any and all conditions of operation, and thereby increase the efficiency in connection with the operation of such engine.

Another object is to control the supply of fuel to an internal combustion engine and ignite the successive charges of such fuel in a manner to produce the best results for successful commercial operation.

These and other objects are accomplished by providing an internal combustion engine with means for supplying successive auxiliary charges of fuel to an auxiliary ignition chamber, where such charges are ignited and in turn ignite successive main charges of fuel within the combustion chamber, and means for regulating the auxiliary and main supply of fuel in accordance with operating conditions.

The invention is illustrated on the accompanying sheet of drawings, in which the single figure is a sectional view of an internal combustion engine embodying my invention.

The various novel features of my invention will be apparent from the description and drawings and will be particularly set forth in the appended claims.

Low grade fuels, such as kerosene and distillate, used in internal combustion engines, are slow in flame propagation, and relatively higher degrees of heat are necessary for perfect ignition and combustion. The ordinary electric spark does not possess the volume to propagate a rapid flame of combustion in the main fuel charge in engines using low grades of fuel at ordinary running temperatures. The combustion of low grade fuel is comparatively slow unless ignited by a flame of comparatively large volume and

high temperature. Slow burning results in what I choose to term burning over or burning beyond the time of exhaust valve opening, followed by preignition, and by reason of the incomplete combustion carried on after a reduction of pressure, there is a residue or deposit of unburned or unconsumed heavier particles of fuel which accumulate over the piston head and on the walls of the combustion chamber, causing a general fouled condition of the engine. Not only are preignition troubles thus encountered, but there is considerable interference in connection with lubrication. Also in time these deposits, after becoming incandescent, become hard and will cut the cylinder walls and piston rings, doing damage to the motor. It is well known that preignition in a motor causes loss of power and decrease in efficiency. History of the ordinary kerosene burning engine of the low compression type, in contradistinction to the Diesel type, shows two methods heretofore in use for burning kerosene. One is to heat the fuel and the intake passages leading to the cylinder and thus form a gas from the fuel that has been previously vaporized while passing through a carburetor or similar device. This fuel or gas being preheated to a fairly high temperature in order to prevent recondensation, materially decreases the motor efficiency by reason of the gas being highly expanded previous to compression. This heating process or method has another objection which is commonly known as breaking up of the fuel by heat; in other words, destroying perfect homogeneity of the fuel and leaving the lower elements thereof to be deposited unburned or in the passages of the carburetor or mixing device, causing a clogged condition.

The second common method is to vaporize the fuel by ordinary means of a Venturi tube in which high velocity of air is created by the intake stroke of the engine, fuel being passed into the high current of air. This does under certain conditions vaporize the fuel, and if not carried too far in long intake pipes or manifolds the result is fairly satisfactory after the engine has become hot, the heat being sufficient to generate this vaporized fuel into a gas after it is admitted to the combustion chamber in the engine. Under these conditions ignition is fairly good by strong electric spark; but the ex-

cessive heat at which the motor has to operate in order to produce fairly good combustion under these conditions is detrimental to lubrication and goes far in the direction of 5 producing preignition by charred particles of carbon deposit from the lubricating oil and fuel, and since gasification is not perfect or complete under the temperature of water jacketed walls, a great waste is carried on. In either of these methods there 10 seems to be considerable waste, since in practice it has been found that to produce the same power for the same length of time a larger quantity of kerosene fuel is used than 15 of gasoline, although the British thermal units of kerosene run considerably higher than in gasoline.

My theory is that perfect combustion does not take place in either of the two methods 20 commonly used in low compression motors of the kerosene burning type, and this theory is strongly substantiated by the fact that most all kerosene burning engines of the low compression type show a great evidence of 25 fuel waste under varying loads; the vaporization being at its best only with the engine operating under wide open throttle. In the volume governing type of internal combustion engine it is well understood that the 30 velocity of air through the Venturi tube is measured by the throttle opening.

In carrying out the objects of my invention, I have provided the combustion chamber 10 of an internal combustion engine with an 35 auxiliary ignition chamber 11, in which is located an igniter 12 for producing a spark to ignite an auxiliary charge of fuel to produce a relatively large hot flash or flame which is forced by the power of the explosion 40 into the combustion chamber wherein the main charge is ignited. This creates an igniting medium for the main charge of comparatively great volume and heat, which sets up rapid combustion and consumes the 45 main charge of any low grade fuel completely. This auxiliary chamber preferably is not surrounded by a water jacket, for the reason that I desire to have the same become heated quickly for economical reasons, 50 and to form a perfect gas highly inflammable that can be easily ignited by an electric spark.

For starting purposes gasoline or other 55 highly volatile fuel may be used in the auxiliary ignition chamber until the walls thereof have become heated. The highly volatile fuel, such as gasoline, may be supplied from any suitable source 13 through a pipe 14 leading into a passageway 15 associated with 60 the auxiliary ignition chamber 11. Interposed between the auxiliary ignition chamber and the passageway 15 is a suction controlled valve 16, which is normally held to its seat 17 by a coiled spring 18 surrounding the 65 stem 19 of the valve. After the walls of

the auxiliary ignition chamber have become sufficiently heated the highly volatile fuel may be shut off and a low grade of fuel, such as kerosene, may be supplied to said ignition chamber through said passageway 70 15 from any suitable source, said low grade fuel passing through a carbureter 20 having a passageway 21 connecting with the passageway 15. The carbureter is provided with a valve 22 for regulating the quality 75 of the auxiliary kerosene charge. To regulate the quantity of the charge to the auxiliary ignition chamber a throttle valve 25 is provided, which is preferably placed in the passageway 21.

The main charge of fuel which is of low grade, such as kerosene, passes through a different carbureter 26 connected to a conduit 27 associated with the intake passageway 28 of the engine. The carbureter is 80 provided with a valve 26^a for regulating the quality of the main fuel charge. A throttle valve 39 is also provided in the fuel charging passageway leading to the intake of the engine for controlling the quantity of main 85 fuel supply. The throttle valves 25 and 39 are interconnected by a link 40, said link being connected to the engine governor (not shown) for reasons to be given hereinafter. The intake passageway 28 is controlled by the 90 suction controlled valve 29, normally held against its seat 30 by a coiled spring 31. The cylinder is provided with the usual 95 exhaust outlet and exhaust valve 33.

In the operation of this kerosene burning engine, and particularly for starting purposes, the gasoline may be turned on to permit successive charges of same to pass into the auxiliary ignition chamber after passing the valve 16 upon each inhalation stroke of the piston 34 of the engine. At the same time successive main charges of the heavy fuel, such as kerosene, are drawn into the combustion chamber past the main inlet valve 29. Upon the compression of the 100 charge of fuel in the combustion chamber of the internal combustion engine, and also of the auxiliary charge in the auxiliary ignition chamber, the auxiliary charge is ignited by an electric spark, causing said auxiliary charge to explode, producing a large hot flame for igniting the main charge of kerosene fuel, the flame caused thereby rapidly propagating and completely consuming all of the fuel charge, whereupon the piston is forced on its 105 expansion stroke for doing work. When the walls of the auxiliary ignition chamber have become sufficiently heated the gasoline may be shut off and the kerosene turned on, the quality of which may be regulated by the valve 22, the auxiliary charge of kerosene being drawn into the auxiliary ignition chamber at the same time the main charge of kerosene is drawn into the combustion 110 chamber of the internal combustion engine. 115

This auxiliary charge of kerosene is ignited by the electric spark, the auxiliary charge readily igniting, due to the extremely hot condition of the walls of the auxiliary ignition chamber in addition to the spark, the result being that the flame caused by the ignition of the auxiliary charge ignites the main charge of fuel in the combustion chamber with a large flame, which is effective in causing complete combustion and for obtaining the greatest efficiency. The quantity of auxiliary charge is controlled by the throttle valve 25 located in the passageway 21, and the quantity of main charge of fuel to the combustion chamber is controlled by the other throttle valve 39. As stated above, these throttle valves are connected by a link 40, which link is connected to the governor (not shown) of the engine. In this way the relative quantities of fuel in the proper proportions are supplied to the auxiliary ignition chamber and the combustion chamber in accordance with the demands of the engine. When the engine is working on a light load and low compression only a relatively small auxiliary charge is necessary, and when the engine is working on heavy loads and high compression a relatively large auxiliary charge is required, in which latter case the throttle valve 25 is more nearly wide open than otherwise would be the case and the throttle valve 39 controlling the main charge is wider open than it would be otherwise; the reverse being true when the engine is operating on light load and low compression. By means of these interconnected throttling valves for controlling the quantities of auxiliary charge and main charge, and the relative proportions of the same, the highest efficiency of the engine may be obtained under varying load conditions, the main charge being completely consumed to produce the desired results.

There may be various arrangements and modifications of my invention other than here shown and described, and it is my intention to claim all such modifications and arrangements thereof which do not involve a departure from the spirit and scope of my invention.

What I claim as new, and desire to secure by Letters Patent, is:

1. In an internal combustion engine, the combination of a cylinder having a combustion chamber, an auxiliary ignition chamber, means for supplying independent charges of fuel to said combustion chamber and auxiliary ignition chamber, and means for automatically controlling the volume of charge to each of said chambers.

2. In an internal combustion engine, the combination of a cylinder having a combustion chamber, an auxiliary ignition chamber, means for supplying independent charges of fuel to said combustion chamber

and auxiliary ignition chamber, and governor controlled means for controlling the volume of charge to each of said chambers.

3. In an internal combustion engine, the combination of a cylinder having a combustion chamber, an auxiliary ignition chamber, means for supplying independent charges of fuel to said combustion chamber and auxiliary ignition chamber, and simultaneously controlled means for controlling the volume of charge to each of said chambers. 70 75

4. In an internal combustion engine, the combination of a cylinder having a combustion chamber, an auxiliary ignition chamber, means for supplying independent charges of fuel to said combustion chamber and auxiliary ignition chamber, and means for controlling the quantity and quality of charges to said chambers. 80

5. In an internal combustion engine, the combination of a cylinder having a combustion chamber, a main fuel inlet and an auxiliary fuel inlet, means for igniting a charge of fuel in said auxiliary inlet for igniting a main charge of fuel in said combustion chamber, and governor controlled means for controlling the quantity of each of the fuel charges. 85 90

6. In an internal combustion engine, the combination of a cylinder having a combustion chamber, a main fuel inlet and an auxiliary fuel inlet, means for igniting a charge of fuel in said auxiliary inlet for igniting a main charge in said combustion chamber, and interconnected governor controlled means for controlling the quantity of each of the fuel charges. 95 100

7. In an internal combustion engine, the combination of a cylinder having a combustion chamber, an auxiliary ignition chamber, means for supplying fuel to the combustion chamber, means for supplying a plurality of different fuels to said auxiliary ignition chamber, means for igniting a charge of fuel in said auxiliary ignition chamber for igniting a charge of fuel in the combustion chamber, a valve for controlling the quantity of main fuel supply, a valve for controlling the quantity of auxiliary fuel supply, and a governor actuated connection between said 105 110 115 valves.

8. In an internal combustion engine, the combination of a cylinder having a combustion chamber, means for supplying fuel thereto, an auxiliary ignition chamber, means for supplying fuel thereto, means for igniting a charge of fuel in said auxiliary ignition chamber to ignite the main charge of fuel in said combustion chamber, and means for automatically controlling the 120 125 quantities of fuel in the main and auxiliary charges and their relative proportions.

9. In an internal combustion engine, the combination of a cylinder having a combustion chamber, a source of fuel supply there- 130

for, an auxiliary ignition chamber, a conduit associated with said ignition chamber, means for supplying high and low grade fuels to said conduit, a suction controlled valve interposed between said auxiliary ignition chamber and said conduit, a suction controlled main inlet valve for said combustion chamber, means for igniting the fuel in said ignition chamber for in turn igniting the fuel in said combustion chamber, and governor controlled valves for controlling the quantities of main and auxiliary fuel charges.

10. In an internal combustion engine, the combination of a cylinder having a combustion chamber, a source of fuel supply therefor, an auxiliary ignition chamber, a conduit associated with said ignition chamber, means for supplying high and low grade fuels to said conduit, a spring-pressed valve interposed between said auxiliary ignition chamber and said conduit, a spring-pressed main inlet valve for said combustion chamber, means for igniting the fuel in said auxiliary ignition chamber for in turn igniting the fuel in said combustion chamber, and governor controlled means for controlling the quantities of fuel supply to said combustion chamber and said auxiliary ignition chamber and also the relative proportions thereof.

11. In an internal combustion engine, the combination of a cylinder having a combustion chamber, an auxiliary ignition chamber, means for supplying charges of fuel to said combustion chamber and said auxiliary ignition chamber, and means for automatically controlling the volume of charge to each of said chambers.

12. In an internal combustion engine, the combination of a cylinder having a combustion chamber, a main fuel inlet and an auxiliary inlet, means for igniting a charge of fuel in said auxiliary inlet for igniting a main charge of fuel in said combustion chamber, and governor-controlled means for controlling the supply of fuel to said inlets.

13. In an internal combustion engine, the combination of a cylinder having a combustion chamber, a main fuel inlet and an auxiliary fuel inlet, means for igniting a charge of fuel in said auxiliary inlet for igniting a main charge in said combustion chamber, and interconnected governor-controlled means for controlling the supply of fuel to said inlets.

In testimony whereof I affix my signature, in the presence of two witnesses.

HARRY C. WAITE.
